CLAIM

The ornamental design for a toilet seat handle, as shown and described.

DESCRIPTION

FIG. 1 is a rear left side perspective view of a toilet seat handle, showing my new design, with the paper covering the adhesive surface partially peeled back;

FIG. 2 is a top perspective view of the toilet seat handle of FIG. 1;

FIG. 3 is a side view of the toilet seat handle the opposite side being a mirror image;

FIG. 4 is a bottom perspective view of the toilet seat handle of FIG. 1;

FIG. 5 is a rear end view of the toilet seat handle of FIG. 1; and,

FIG. 6 is a front end view of the toilet seat handle of FIG. 1.
